FOUNTAIN-TYPE COMB

Charles A. McClure, Chicago, Ill., assignor of one-half to Mary A. Sribike

Application November 17, 1944, Serial No. 563,871

2 Claims. (Cl. 132—13)

This invention relates to improvements in fountain type combs, that is, a form of comb in which a reservoir or equivalent container is provided, this to hold chemical, medicinal and pharmaceutical preparations, the latter to be distributed, by properly arranged ports, to the teeth of the comb.

As implied in the preceding opening statement of the invention, I am aware that fountain combs, brushes and the like are not new. Therefore, it is the purpose of the instant invention to generally improve upon known and patented devices in this category, this by providing a novel and improved arrangement of structural features and parts.

Briefly, the preferred embodiment of the invention comprises a cylindrical elongated barrel attached to the back of the comb, this constituting a container or reservoir for hair oil, dyes and the like, there being means provided at opposite ends, one arrangement to expedite filling of the barrel, and the other having a spring-return push-button, this for operating a multiple control valve unit which coacts therewith and with the discharge ports in the back of the comb.

Novelty is believed to reside in the provision of substantially L-shaped discharge ports, these having their intake ends located in the valving area of the barrel and their discharge ends located to properly feed and distribute the contents of the barrel over the surfaces of the teeth, there being a push button controlled rod located in the barrel and this having valve elements for co-acting with and properly opening and closing the ports.

Other features and advantages will become more readily apparent from the following description and the accompanying illustrative drawings.

In the drawings, wherein like numerals are employed to designate like parts throughout the same:

Figure 1 is a side elevational view of a comb constructed in accordance with the principles of this invention.

Figure 2 is a view like Figure 1 with parts broken away and shown in section.

Figure 3 is an enlarged cross-section on the plane of the line 3—3 of Figure 2.

Figure 4 is a fragmentary detail sectional and elevational view of one end portion of the comb and associated barrel and push button assembly.

Figure 5 is a similar fragmentary elevational view on somewhat the same scale, this showing the spider for accommodation of one end of the reciprocatory multiple valve rod.

Referring now to the drawings by distinguish-

ing reference numerals, the comb, of suitable material and proportions, is generally denoted by the numeral 6. As indicated, the back 7 of the comb is provided with an elongated cylindrical barrel 8 whose ends terminate preferably inwardly of the transverse ends of the comb proper. This barrel serves as a reservoir or container for the solutions and compounds utilized. In practice, these may be chemicals such as hair dyes, a special medicament for treatment of the hair and scalp, or simply hair grooming oils. The preparations are placed in the barrel at the filler end at the right, this being provided with an appropriate removable screw-plug 8a for such purposes.

For convenience, the chamber which forms the reservoir proper is denoted by the numeral 9 in Figure 5 in which it will be observed that at the center thereof I provide a suitable guide spider 10. This is adapted to receive the reduced guide shank 11 on one end portion of the reciprocatory valving or control rod 12. This is located in the left-hand half-portion of the barrel. At its opposite end it is provided with a similar guide and assembling extension 13 which operates through coacting guides 14 and 15 which serve as fluid-tight packing elements. The extreme end portion passes through a guide and packing ring 16 which is located in a cap 17 at the left-hand end of the barrel. But before discussing these details I would direct attention to the fact that the rod is substantially cylindrical in cross-sectional form as seen in Figure 3 and on its bottom is provided with substantially flat rectangular inserts preferably of rubber as indicated at 18. These are valve elements and serve to normally cover or close the intake ends of the L-shaped ports 19, these formed in the back of the comb and having their discharge ends arranged to deliver and spread the contents of the barrel over the teeth of the comb.

Referring again to Figure 4, the extended end portion 18 of the valving rod is screw-threaded and connected as at 20 to a push-button 21, the latter slideable in a socket 22 provided in the cap 17. A coil spring is located in this socket 22 as indicated at the point 23 and surrounds the extension 13, bearing at one end against the push button and at the opposite end against the guide 14, the latter serving as a stop or shoulder therefor. The tendency of the spring is to push the button out to projected position. Thus, under the influence of the spring the valve rod 12 is normally held in a position whereby all of the valve elements 18 close their respective feeder ports. When, however, the button 21 is pushed against

the tension of the spring 23 the rod with all of the valve elements 18 thereon is pressed into a position whereby the valve elements 18 uncover their ports. It follows that the liquid contents of the chamber 8 therefore flows out through the then temporarily opened ports and flushes over the teeth of the comb as is accomplished in fountain type appliances of this class.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

1. In a fountain-type comb of the class described, a body including a rigid back portion and associated teeth, said back being provided with a longitudinal barrel, said barrel constituting a reservoir for a predetermined solution or preparation, having closures for opposite ends of said barrel, L-shaped ports formed in said back and having the discharge ends opening through one surface and the intake ends opening into the chamber formed in said barrel, a reciprocatory valve rod in said barrel provided with longitudinally spaced rubber inserts, said inserts constitut-

ing valve elements and said valve elements covering said intake ports, said valve rod having its opposite ends reduced, and guides in the barrel for coaction with said reduced ends, and a spring-returned button on one end connected to one of said reduced ends, whereby to normally hold the valve elements in closed position, in the manner and for the purposes described.

2. In a fountain-type comb of the class described, a body including a rigid back portion and associated teeth extending laterally therefrom, said back portion being provided with an integral longitudinally extending barrel, said barrel constituting a reservoir and having closure means at opposite ends, said body being further provided with L-shaped ports, said ports having their discharge ends opening through one surface of the back for coaction with said teeth, the inner intake ends of said ports opening into said reservoir, a reciprocatory valve rod mounted in said reservoir and provided with valve elements covering the intake ends of said ports, spring means coacting with the valve rod for holding the valve elements normally in position covering said ports, said valve rod having its opposite ends reduced, guide means in said barrel, with which said reduced ends slidably coat, one of said reduced ends extending beyond the adjacent end of the barrel and being provided with a push-button.

CHARLES A. McCLURE.
